(57) **CLAIM**

I claim the ornamental design for an orange and black cellular telephone charger power cord, as shown and described.

DESCRIPTION

FIG. 1 is a top view of the orange and black cellular telephone charger power cord (the bottom view being a mirror image of the top view).

FIG. 2 is a rear view of the orange and black cellular telephone charger power cord.

FIG. 3 is a front view of the orange and black cellular telephone charger power cord.

FIG. 4 is left side view of the orange and black cellular telephone charger power cord; and,

FIG. 5 is a right side view of the orange and black cellular telephone charger power cord.

The drawings have been lined to indicate the colors orange and black.
